Term of patent 14 years

Int. Cl. D16—08

U.S. Cl. D57—1

FIG. 1 is a perspective view of a pair of spectacles showing my new design;

FIG. 2 is a front elevational view thereof.

FIG. 3 is a sectional view taken along line 3—3 as shown in FIG. 2, the temple being fragmentarily shown for convenience of illustration.

The side not shown has substantially the same appearance as the side shown.

I claim:

The ornamental design for a pair of spectacles, substantially as shown and described.
